SEWING MACHINE TAKE-UP MECHANISM

John Roger Oliver, Medfield, Mass., assignor to
Reece Shoe Machinery Company, Boston,
Mass., a corporation of Maine

Original application June 4, 1931, Serial No.
542,048. Divided and this application May 7,
1932, Serial No. 609,827

8 Claims. (Cl. 112—57)

This invention relates to sewing machine take-up mechanism, and more particularly to the take-up mechanism of power driven sewing machines such as those used for stitching leather or shoes, 5 a typical instance being the so-called outsole stitcher by which the outsole and welt of a shoe, are sewed together. The present application is filed as a division of copending parent application Serial No. 542,048 filed June 4, 1931 to which 10 reference may be made for various details not particularly herein described and claimed.

The general object of the present invention is to afford a sewing machine of the power driven class having a take-up and operating mechanism 15 therefor which will be efficient and smooth of action.

Other and more specific objects and advantages 20 of the present invention will be pointed out in the hereinafter following description of an illustrative embodiment thereof, or will be understood to those conversant with the subject. To the attainment of such objects and advantages 25 the present invention consists in the novel sewing machine take-up mechanism and the novel features of operation, combination and construction herein illustrated or described.

In the accompanying drawings Figure 1 is a 30 front elevation of the upper portion or stitching head of a shoe outsole stitching machine constructed in accordance with the present invention, but with a number of parts omitted or broken away for purposes of better illustration.

Fig. 2 is a fragmentary front view showing in 35 particular the parts concerned in the take-up mechanism.

Fig. 3 is a right elevation of the sewing machine with certain parts omitted or broken away.

Fig. 4 is a diagram indicating the nature of the 40 motions of the several stitching instruments including the take-up, the diagram representing one complete stitch cycle or rotation of the operating shafts, and the zero point representing the positions of the several instruments at the preferred stopping point of the machine.

The fixed frame part or head 20 may be located 45 at the top end of a post so that the operator may stand while handling the work. Bearings 21 give support to an operating or drive shaft 22 which 50 may be power rotated, for example through a belt and pulley from a motor at the base of the machine. Above the drive shaft is a second shaft 23 turning in an outer bearing 24 near its left end and in two frame walls, namely a left wall 25 and a right wall 26 upstanding from the base 20.

The second operating shaft 23 will be referred to as a stitching shaft, being connected for driving the needle and other instruments as explained in the parent application. The drive is communicated from the drive shaft to the stitching shaft by a system of cranks and links comprising a left crank 27 on the drive shaft 22, a right crank 28 on the shaft 22, a left crank 29 on the shaft 23 and a right crank 30 on the shaft 23; the two left cranks 27 and 29 being connected by 10 a rod 31, and the two right cranks 28 and 30, having a different timing from the left cranks, being connected by a rod 32. A hand wheel 34 on the shaft 23 is for the purpose of rotating it manually when desired. 15

Between the frame walls 25 and 26 the upper or stitching shaft 23 is provided with cams or cranks for effecting operations of certain of the stitching instruments. The take-up however forming especially the subject of this application is preferably 20 operated from the drive shaft 22, which carries an eccentric 41 for this purpose, as will be described.

The stitching instruments, in a machine of the type referred to, may include the following. 25 The stationary work support A is in the form of a bracket attached to the left frame wall 25, its forward extremity arranged to support the work or shoe in proper relation and being apertured for the alternate passage of the needle 30 from above and the awl from beneath. The shoe is preferably held manually in inverted position with its outsole substantially horizontal, the welt and outsole overlying the work support to receive the interlocking upper and under threads, the 35 former supplied by shuttle and bobbin and the latter being subject to the action of the take-up and other control means as tension devices, thread lock, etc.

Above the work support, to overlie the work is 40 the presser foot B, operable as described in the parent case. The needle C is of the curved barbed type, its barbed point penetrating the work from above and receiving a loop of under thread below the work. The needle is steadied 45 by a needle guide D. These elements B, C and D are actuated from the stitching shaft 23.

The awl F may also be actuated from the shaft 23 and is employed not merely to puncture the work but to effect the feed thereof. The awl is 50 bodily mounted on a horizontally reciprocable feed slide G likewise operated from the stitching shaft. Below the work are a looper H and a thread hook I. The looper is operated to feed or supply the under thread, which may be waxed, 55

to the barb of the advanced needle, in which the thread hook cooperates with the looper, each of these having particular movements toward and from the stitching point.

5 The take-up device J which forms the particular subject of this application is in the form of a rotary member or disk J carrying a thread pulley J' and operated as will be further described. The function of the take-up is to act 10 upon the under thread in a manner to let out the thread while the thread is being passed over the shuttle and to take it up again thereafter, preferably to an extent causing the under thread to draw down the upper thread slightly into or 15 below the top surface of the work at the completion of each stitch.

The shuttle K is shown of the rotary type adapted to engage and pass itself through a loop of under thread when held above the work by the 20 needle and thread finger L, the shuttle thereby removing the thread from the needle and passing it over the shuttle to interlock it with the upper thread supplied by the usual bobbin mounted in the shuttle. The shuttle is shown mounted on 25 an inclined shaft K² which may be rotated at uniform speed.

The preferred timing and relative movements of the several stitching instruments B to L inclusive may be as indicated on the diagram Fig. 4, 30 in which the motion of the take-up J, coordinated with the other instruments, particularly concerns the present invention.

The take-up J is shown in the form of a thin 35 rotary disk with its left face or side clear and carrying the grooved thread wheel J' near its periphery, the thread wheel thereby being bodily shifted circularly as the disk rotates about its axis. As best seen in Figs. 2 and 3, the movable or planetary thread wheel or pulley J' cooperates 40 with a pair of thread guides or pulleys mounted on a fixed support or bracket 163. Thus the thread may come from a rear supply point, through a thread lock, and first pass over the top of the rear fixed pulley 164 and thence down 45 and around the shiftable or planetary guide or pulley J' and thence up and around the forward side of the front fixed pulley 165 and thence up and into the thread channel within the looper H and from the looper to the work.

50 The specific arrangement and construction of take-up may be varied in accordance with conditions. The take-up or disk J is shown as having a hub or extension J² as shown in Figs. 2 and 3, which extends to the right only, so that 55 there is no obstruction at the left face of the disk J to interfere with the thread movements. The disk hub is enclosed, with easy running bearings, within a fixed housing or support 166 arranged in a fore and aft plane.

60 The take-up disk J may be connected for rotation at predetermined but variable speed as follows. At the right or interior side of the disk is an operating crank or pin 167, shown above the axis of the disk, and by which the disk may 65 be rotated for its take-up and thread giving movements. The movements of the pin 167 may be derived from the eccentric 41 on the drive shaft 22. A strap 168 surrounds said eccentric, and this strap has an extended arm or rod 169 carrying at its front end the crank or pin 167.

As the center x of the eccentric 41 travels 70 around the shaft 22 an orbital motion is communicated to the pin 167 as follows. In a radial slot 170 in the arm 169 is located a block 171 75 swivelled on a fixed axle 172. As the eccentric

travels clockwise about its axis the pin 167 will travel counterclockwise about its orbit, but at varying speeds and at varying distances from the axis of the disk J. To allow this motion the pin is mounted, not directly on the disk, but on a block 173 slidable radially in slot 174 in the hub of the disk.

As shown, the eccentric is advancing clockwise, and the pin and disk consequently advance counterclockwise continuously but at varying speed through the cycle of the machine. The radius from 172 to x is approaching minimum 10 while the radius 172—167 is approaching maximum and the angular swing of arm 169 maximum, so that the thread wheel will soon be reTRACTING downwardly at maximum speed. Later when the center x nears its other extreme position the conditions will reverse and the pin and thread wheel will return upwardly at slower velocity. Without showing the angular motion changes of 20 the disk itself, let it be said that the fast and slow orbital motions of the planetary thread wheel during the taking up and thread giving motions afford a very effective cooperation with the other stitching instruments; it being borne in mind 25 that the take-up and give actions result from the travel of the planetary guide or pulley J' in relation to the fixed pulleys 164, 165, and that during the slow movement of the pulley J' around the lower part of its path the action on the thread is practically zero.

The described arrangement is found to be very 30 easy working as well as compact and durable. The cooperation of the shifting take-up guide or pulley J' with the two fixed pulleys 164 and 165 give the result that a relatively small retracting movement of the take-up affords a double extent of actual take-up of thread. The take-up motion as a whole is a circular motion so that the usual whipping action of a take-up lever is 40 eliminated.

The timing of the take-up action in relation to the other stitching instruments may be as indicated in the diagram of Fig. 4. An under thread lock and/or tension will be understood, locking 45 the thread during taking up, and allowing a measured length to be drawn from the supply at another time, as is well understood with machines of the kind. For example the thread lock may lock and release as indicated in the diagram 50 Fig. 4 in relation to the take up motion.

Having thus described a sewing machine embodying a take-up mechanism embodying the principles of the present invention, it is to be understood that the invention is not limited to 55 matters of operation, arrangement or structure except to the extent set forth in the respective claims.

What is claimed is:

1. In a power operated barbed-needle two-thread stitching machine, a transverse shaft, a work support, a shuttle above the work support adapted to take an under thread loop from the retracted needle and pass the loop over itself, and a take-up below the work support adapted to give out and take up the under thread, comprising a disk, a thread guide at the periphery of the disk and means for rotating the disk continuously at variable speed including a crank connected to the disk and a connection from the shaft to the crank. 60

2. In a power operated barbed-needle two-thread leather stitching machine, an operating shaft, a work support, a shuttle above the work support adapted to take an under thread loop from the retracted needle and pass the loop over 65

5 itself, a looper below the work support to place under thread upon the needle barb, and a take-up below the work support adapted to give out and take up the under thread, comprising a vertical disk, a thread guide near the periphery of the disk, means for rotating the disk including a crank connected to the disk and a connection from the shaft to the crank, a fixed position pulley over which the under thread passes from the supply to the disk guide, and a second fixed position pulley over which the thread passes from the disk guide to the looper.

10 3. In a leather stitching machine of the class described, a guide pulley for supply thread, a take up pulley receiving thread from the guide pulley, a rotary carrier for the take up pulley, and means for rotating the carrier, comprising an operating shaft, a crank or eccentric actuator on the shaft, and a connecting rod from the 15 actuator to the carrier, the connecting rod being slidable on a fixed center, its free end describing an orbit around the carrier axis, and a pin and slot connection from such free end to the carrier.

20 4. In a power driven lock stitch leather or shoe stitching machine, an operating shaft, a work support over which the work feeds, a barbed needle connected to penetrate the work from above, receive a loop of under thread and retract, a shuttle to receive the under thread and loop it over the upper thread, a looper below the work support to apply a loop of under thread to the needle, and take up mechanism comprising a carrier mounted below the looper for rotation about a substantially horizontal axis, a connection from the shaft for rotating the carrier in time with the needle, shuttle and looper, a thread pulley on the carrier and shifted thereby between advanced and retracted positions, a 25 guide pulley near the advanced position of the thread pulley and delivering supply thread thereto from a thread lock means, and a second guide pulley between the advanced position of the thread pulley and the looper.

5 5. In combination, a take up disk J, an operating eccentric 41, a connecting rod 169 actuated by the eccentric and rocking on a pivot 172, and a pin 167 at the free end of the rod having sliding connection with the disk.

10 6. In combination, a rotatable take-up disk having a thread guide adjacent its periphery, an operating eccentric, a connecting rod actuated by the eccentric, a pivot on which the connecting rod slides and rocks so that its free end describes an orbit in a direction the opposite to the rotation of the eccentric, and a sliding connection between the free end of the rod and the take-up disk whereby the disk is rotated continuously at alternately fast and slow speeds.

15 7. The combination as in claim 6 and wherein in the thread guide is located at such position on the take-up disk that it retracts orbitally at relatively high speed for the take-up motion, and returns orbitally at relatively slow speed for 20 thread giving motion.

25 8. In a power operated, barbed-needle two-thread stitching machine, in combination with the operating shaft and the needle and looper actuated therefrom, means for taking up the under thread, comprising a rotary member carrying eccentrically a thread pulley, connections from the operating shaft for rotating said member continuously to shift said pulley bodily 30 around a circular path, and thread guides located exterior to the path of the shiftable pulley over which guides the supply thread passes to and from the shiftable pulley, whereby in one part of such rotation the pulley is shifted from its advanced position nearest said guides 35 with a retracting motion to its retracted position to take up such thread and in the remainder of such rotation is shifted from its retracted to its advanced position to give thread; the connections from the operating shaft being such that the retracting rotation of the pulley is at a relatively fast while its return rotation is at a relatively slow effective speed.

40 JOHN ROGER OLIVER.
